Primary Examiner — Kevin Rudzinski(74) *Attorney, Agent, or Firm* — Keisling & Pieper PLC; Stephen D. Schrantz(57) **CLAIM**

The ornamental design for a light fixture screen, as shown and described.

DESCRIPTION

FIG. 1 is a top perspective view showing my new design;
 FIG. 2 is a bottom perspective view thereof;

FIG. 3 is a front view thereof, the rear view being a mirror image of the front view;

FIG. 4 is a right side view thereof, the left side view being a mirror image of the right side view;

FIG. 5 is a top view thereof;

FIG. 6 is a bottom view thereof; and,

FIG. 7 is an exploded view thereof.

The broken line illustration of portions of the light fixture screen forms no part of the claimed design.

1 Claim, 4 Drawing Sheets# US D670,855 S
